COMBINED SPRAYER NOZZLE AND HANDGRIP

Herman P. Heydt, Minneapolis, Minn.

Application September 4, 1948, Serial No. 148,476

Term of patent 14 years

(CL. D83—1)

To all whom it may concern:

Be it known that I, Herman P. Heydt, a citizen of the United States, residing at 4445 28th Avenue South, Minneapolis, county of Hennepin, State of Minnesota, have invented a new, original, and ornamental Design for a Combined Sprayer Nozzle and Hand Grip, of which the following is a specification, reference being had to the accompanying drawing, forming a part thereof.

Fig. 1 is a side elevation of a combined sprayer nozzle and hand grip, showing my new design, and

Fig. 2 is a top plan view thereof.

The dominant features of my design reside in the portions shown in full lines.

I claim.

The ornamental design for a combined sprayer nozzle and hand grip, substantially as shown and described.

HERMAN P. HEYDT.
